(57) **CLAIM**

The ornamental design for a tire tread, as shown and described.

DESCRIPTION

FIG. 1 is a perspective view of a tire tread of the present application;

FIG. 2 is a front view thereof;

FIG. 3 is a side view thereof;

FIG. 4 is an enlarged partial, perspective view thereof;

FIG. 5 is an enlarged partial, front view thereof; and,

FIG. 6 is an enlarged partial, side view thereof.

The broken lines and the region between the broken line showings of the inner bead and the sidewall, illustrated in FIGS. 1, 3, 4, and 6, depict subject matter that forms no part of the claimed tire tread design, and are included for the purpose of illustrating the full tire. The tread pattern is understood to repeat throughout the circumference of the tire. The other side is identical to the illustrated side views of FIGS. 3 and 6.
